UNITED STATES PATENT OFFICE.

HERMAN SCHWARZ, OF NEW YORK, N. Y.

CAP.

SPECIFICATION forming part of Letters Patent No. 408,934, dated August 13, 1889.

Application filed February 1, 1889. Serial No. 298,330. (No model.)

To all whom it may concern:

Be it known that I, HERMAN SCHWARZ, of the city, county, and State of New York, have invented a new and useful Improvement in 5 Head-Wear, of which the following is a full, clear, and exact description.

My invention relates to an improvement in head-wear, and has for its object to provide an ear-flap for hats, caps, and similar articles 10 which, when not in use, will be concealed from view; and a further object of the invention is to provide ear-flaps for hats, caps, and similar articles which will not in the slightest interfere with or detract from the shape of the 15 article to which they are attached.

Another object of the invention is to provide an ear-flap which, when in use, will also cover and protect the forehead of the wearer.

The invention consists in an article of manufacture, consisting of an article of head-wear 20 having the material at the bottom edge turned inward within the crown and extended above and across the visor, and in the novel construction and combination of the several parts, 25 as will be hereinafter more fully set forth, and pointed out in the claims.

Reference is to be had to the accompanying drawings, forming a part of this specification, in which similar figures of reference indicate 30 corresponding parts in all the views.

Figure 1 is a perspective view of a cap having my improvement applied. Fig. 2 is a central vertical section through the same. Fig. 3 illustrates the cap upon the head of a 35 person, the ear-flap being illustrated as down over the ears and forehead; and Fig. 4 is a detail view of the under side of the front part of the cap.

In carrying out the invention the body 10 40 of the hat, cap, or other article of wearing-apparel is formed to any usual or desired shape, the cap illustrated being provided with a visor 11, the material of the body of the cap extending down over and forming the covering of the said visor. The body 10 is made 45 of greater length than is necessary for the actual formation of the cap, for instance, and the surplus material at the bottom is carried upward within the crown to a contact with

the inner face of the body, as illustrated at 50 12 in Fig. 2, forming ear-flaps. The inwardly-folded material at the front is slit or cut, as at 13, the slit or cut extending a distance nearly equal to the length of the visor. In the slit or cut 13 the stiffening 14 of the visor 55 is placed, the said stiffening being secured to the edges of the slit or cut and forming a gôre.

When the flap or inner folded material is carried upward within the crown, as illustrated in Fig. 2, the exterior of the article of head-wear does not indicate in the least that an ear-flap is provided for the same, and as the material is preferably of a single thickness the contour or style of the article is not 60 changed, and the said article is not rendered bulky in appearance, as is ordinarily the case when the old style of flap is employed, the said flap occupying a position on the exterior of the article of head-wear in full view. 70

When the inner fold or flap is to be used for the purpose of keeping warm the rear portion of the head, the ears, and the forehead of the wearer, before placing the cap or other article of head-wear containing my improved 75 flap upon the head the inwardly-folded material is folded outward, and in this position the cap is introduced upon the head, whereupon the flap, which is continuous, as illustrated in Fig. 3, will neatly cover the back of 80 the head, the ears, and likewise the forehead without detracting from the general appearance of the article.

Having thus described my invention, I claim as new and desire to secure by Letters Patent— 85

As an improved article of manufacture, an article of head-wear having the material constituting the body extending in one continuous piece below the lower edge of the body to form ear-flaps, the said extension being turned 90 up within the crown when not in use and having in its front portion a cut or slit 13, to the edges of which the stiffening of the visor is secured, as specified.

HERMAN SCHWARZ.
